US00D927940S

(12) **United States Design Patent** (10) **Patent No.:** **US D927,940 S**
Callinan et al. (45) **Date of Patent:** **** Aug. 17, 2021**

(54) **CONTAINER ENCLOSURE**

(71) Applicant: **BottleKeeper, LLC**, Houston, TX (US)

(72) Inventors: **Adam Callinan**, El Segundo, CA (US);
Matthew T. Campbell, Phoenix, AZ (US)

(73) Assignee: **BottleKeeper, LLC**, Houston, TX (US)

(**) Term: **15 Years**

(21) Appl. No.: **29/749,186**

(22) Filed: **Sep. 3, 2020**

Related U.S. Application Data

(63) Continuation of application No. 29/707,679, filed on Sep. 30, 2019, now Pat. No. Des. 896,040, and a continuation of application No. 29/707,683, filed on Sep. 30, 2019, now Pat. No. Des. 896,041, which is a continuation of application No. 29/694,840, filed on Jun. 13, 2019, now Pat. No. Des. 862,178, said application No. 29/707,679 is a continuation of (Continued)

(57) **CLAIM**

The ornamental design for a container enclosure, as shown and described.

DESCRIPTION

FIG. 1 is an isometric view of a rear, top, and left side of an ornamental design for a container enclosure;

FIG. 2 is a front elevational view of the container enclosure of FIG. 1;

FIG. 3 is a rear elevational view of the container enclosure of FIG. 1;

FIG. 4 is a right side elevational view of the container enclosure of FIG. 1;

FIG. 5 is a left side elevational view of the container enclosure of FIG. 1; and,

FIG. 6 is a top plan view of the container enclosure of FIG. 1.

The dash-dash-dash lines are for the purpose of illustrating environmental structure and form no part of the claimed design. The dash-dot-dash lines form no part of the claimed design and represent boundary lines.

1 Claim, 4 Drawing Sheets

Related U.S. Application Data

application No. 29/694,838, filed on Jun. 13, 2019,
now Pat. No. Des. 864,672.
